UNITED STATES PATENT OFFICE.

ERNEST P. VINCENT, OF NEW YORK, N. Y.

SIGN.

1,421,044.

Specification of Letters Patent. Patented June 27, 1922.

Application filed April 20, 1917, Serial No. 163,368. Renewed April 27, 1922. Serial No. 557,034.

To all whom it may concern:

Be it known that I, ERNEST P. VINCENT, a citizen of the United States, residing at the borough of Manhattan, in the county 5 of New York and State of New York, have invented certain new and useful Improvements in Signs, of which the following is a specification, reference being had therein to the accompanying drawing.

16 My invention relates to improvements in signs, and has particular reference to advertising signs and especially those which are illuminated. The invention has for one of its principal objects the production of a sign 15 which can be read at a distance without having to stand directly in front of the same. One of the principal objections to the present forms of illuminated signs is the fact that unless standing almost opposite 20 the sign, it cannot be read from a distant point. In other words, a sign in front of a building when illuminated is difficult to read on coming down the street until almost opposite thereto owing to the confusion of 25 light rays and dazzling effect of the lights. According to my preferred method of construction, the characters such as the letters 30 of a sign are preferably provided with extending members or ribs following the outlines of the characters and by which they 35 may be discerned at a considerable distance without having to stand in front of the sign, and this applies to the illuminated and non-illuminating type of signs.

40 In the accompanying drawings, I have illustrated in Fig. 1, a non-illuminated type of sign showing the letter H according to one application of my invention. Fig. 2 is a similar view showing the backboard of 45 the character cut out to conform to the outlines of the character. Fig. 3 is a similar illustration showing an application of the invention to an illuminated character. Fig. 4 illustrates another modification, Fig. 5 a 50 framed backboard form of character, Fig. 6 another illuminated form showing the outline of the letter in members of modified construction. Fig. 7 illustrates various modifications of such members. Fig. 8 is 55 a view showing the relative position of the lights and the member by which the character is outlined. Figs. 9 and 10 are views similar to Fig. 8 illustrating modifications, Fig. 11 a front elevation of a suitable form 60 of bolt for retaining the outlining members, Fig. 12 a modified form of the same.

Instead of painting the character upon a flat surface or depressing the same therein or outlining it in other suitable manner, the same is preferably outlined by strips of material such as 13, which may be secured between the forked ends 14 of bolts such as indicated in Fig. 11 or in any other suitable manner. By constructing the character in this manner the color of the members 13 60 being of course contrastingly different from the color of the base 14, the character can be read at greater distance without the necessity of standing opposite to the same. For accentuating the character, the base 14 70 may of course be cut to conform therewith as indicated in 14' in Figs. 2 and 3 or may be formed in boxlike manner as indicated at 15 in Fig. 5.

75 For illumination purposes, the lights such as incandescent lamps may be secured beneath the outlining members as indicated by the reference character 16 in Fig. 3. By this arrangement the character is illuminated on all sides and stands out beyond the 80 lights so as to be seen from almost any angle and at the greatest distance.

By referring now more particularly to Figs. 6 and 7, it will be observed that various forms of outlining members may be 85 employed. The form illustrated at 17 is preferably a straight flat member similar to 17 indicated by the reference character 13. 18 indicates the inverted V type. 19 shows the same in curved arrangement. 20 presents a flat surface, 21 a round rod or tubular arrangement, 22 a concave surface, and 23 an angular convex-like surface. These members of course may be connected to the baseboard or body portion of the sign either 90 by continuous strips of material such as 24 or by bolts such as illustrated in Figs. 11 and 12. In using the form of bolt or holder shown in Fig. 12, it may be secured upright as shown in Fig. 9 for holding an 100 outlining member such as shown in Fig. 6, or it may be used in its inverted position to hold a rounded member such as 21 shown in Fig. 8. When the forked form of holder or bolt shown in Fig. 11 is employed, the outlining member 13 is preferably retained above the light 16 as shown in Figs. 3 and 10. In other forms of outlining members such as shown in Figs. 8 and 9, the lights 16 may be opposed at the sides as shown, 110 but in any event the lights are preferably closer to the baseboard or body portion of

the sign than the projecting margin of the outlining members as shown, thus preserving the outline of the characters and giving prominence thereto so as to avoid the loss 5 of the same in the light rays. In other words, it is of importance that the outlining member project beyond the lights so as to receive the light rays upon the surface thereof and outline the same sharply upon 10 the face or body portion of the sign, which being in contrasting color clearly pronounces or defines the character such for instance as a white letter upon a black face or body of a sign, or a black letter upon a 15 white face or body portion of a sign.

In the use of such form of outliner as illustrated at 19, 22 and 23, or in fact in any of the forms, it may be desirable to use outliners of transparent material such as glass 20 or other suitable composition.

Of course it will be understood that various modifications may be made in the construction and arrangement of parts without departing from the spirit of the invention 25 as claimed.

I claim.

1. A sign having a character projecting from the base thereof, said character of substantially flat material substantially at right 30 angles to said base.

2. A sign having a character projecting from the base thereof, said character of substantially flat material substantially at right angles to said base and lights reflecting on 35 said projecting character.

3. A sign having a character projecting from the base thereof, said character of substantially flat material substantially at right angles to said base, and in combination there- 40 with a duplication of said character forming or in combination with said base and presenting a face at right angles to the flat surface of said first mentioned character, the outline of said first mentioned character being central with respect to said base 45 character.

4. A sign having a character projecting

from the base thereof, said character of substantially flat material substantially at right angles to said base, and in combination therewith 50 a duplication of said character forming or in combination with said base and presenting a face at right angles to the flat surface of said first mentioned character, the outline of said first mentioned character being central with respect to said base character, and lights between said first mentioned character and said base character. 55

5. A sign having a character projecting from the base thereof, said character of substantially flat material substantially at right angles to said base, and in combination therewith 60 a duplication of said character forming or in combination with said base and presenting an outstanding face to said flat 65 surface of said first mentioned character, the outline of said first mentioned character being central with respect to said outstanding character and lights between said base and said outstanding character. 70

6. A sign having a character projecting from the base thereof, said character of substantially flat material substantially at right angles to said base, and in combination therewith 75 a duplication of said character forming or in combination with said base and presenting an outstanding face to said flat surface of said first mentioned character, the outline of said first mentioned character being central with respect to said outstanding character. 80

7. A sign having a character projecting from the base thereof, said character of substantially flat material substantially at right angles to said base, and in combination therewith 85 lights beneath the edge of said character and above said base.

In testimony whereof I hereunto affix my signature in the presence of two witnesses.

ERNEST P. VINCENT.
